PLATE SPRING

Theodore R. Weber, Latrobe, Pa., assignor to
American Locomotive Company, New York,
N. Y., a corporation of New York

Application May 17, 1939, Serial No. 274,157

2 Claims. (Cl. 267—54)

The present invention relates to plate springs and more particularly to spring end clips therefor.

An object of the present invention is to provide a spring end clip for a spring hanger which may be assembled with and disassembled from a spring without in any way disturbing the plate assemblage.

A further object is to provide, in a clip as aforesaid, means preventing the loss from the spring of the end portion of the main plate or of one of the other plates associated with the clip, if such end portion should break off in service.

A further object is to provide a clip having a liner or wear plate for supporting the spring hanger.

Other and further objects of and advantages achieved by the present invention will be apparent from the following description of an approved embodiment thereof, and the claims appended hereto.

Referring to the drawing forming a part of this application, Figure 1 is a side elevation of a semi-elliptic spring embodying the present invention, the spring end clip and adjacent portion of the spring at the right hand side of the spring being shown in section; Fig. 2 is a bottom view of the spring of Fig. 1; and Figs. 3, 4 and 5 are enlarged views of the clip, Fig. 3 being a side elevation, Fig. 4 an end view viewed from the right of Fig. 3, and Fig. 5 a bottom view.

The semi-elliptic spring 1 comprises a plurality of plates secured together by a spring band 2. Each of the plates is speared at its ends. The main plate 3 has an elongated orifice 4 in each of its end portions, each of the orifices being spaced from the adjacent end of the spring. The second plate 5 has a similar but slightly longer elongated orifice 6 disposed in alignment with each of the orifices 4, and the third plate 7 has a shorter orifice 8 in alignment with each of the orifices 6. Each set of three aligned orifices forms a receptacle 9 for a purpose later to be described.

A spring end clip 10 is carried by the spring at each of its end portions. Each clip consists of a body portion 11 having a curved outer face 12 and a flat inner face 13. Two longitudinally spaced flanges 14 extend outwardly from the body portion 11, each having a groove 15, the grooves being opposed to each other. A curved liner or wear plate 16 is disposed on the face 12 and is held thereon against vertical and longitudinal displacement movement by the grooves 15, in each of which an end of the liner 16 fits.

The liner is held against transverse displacement movement by the hanger (not shown) when the clip is in use. When the liner becomes worn, it may be replaced simply by sliding out the old liner and sliding in a new one.

A lug 17 projects inwardly from the face 13. It includes an elongated major part 18 and a smaller part 19 of the same width as the part 18. The corner formed by the junction of the lug with the inner face 13 is rounded out by a fracture-resisting groove extending completely around the lug. When the clip is assembled with the spring, the lug is disposed within the receptacle 9 and the inner face 13 is opposed to the outer face 20 of the main plate. A resilient sheet of material 21 is disposed between the faces 13 and 20 so that there is no hard steel connection between the clip and main plate.

The major part 18 has working clearance in the orifice 4, and its elongation prevents turning of the clip relative to the spring. The part 18 has greater clearance in the orifice 6, which allows free flexing of the spring without danger of the clip interfering therewith. The part 19 is disposed in the orifice 8 and has a part 22 projecting therefrom, beyond the inner face of the plate 7, which plate extends at either end beyond the ends of the adjacent plate inward therefrom in the usual manner. An orifice 23 is formed in the part 22 and a cotter pin 24, disposed therein, prevents vertical displacement movement of the clip relative to the spring.

Each clip further comprises two lugs 25 projecting from the inner face 13, one from each of the corners of the clip, which, when the clip is assembled with the spring, are adjacent an end thereof. The lugs 25 are shown projecting substantially the thickness of two plates. Each lug is triangular in shape and has a longitudinal face 26 in line with a longitudinal edge of the clip, a transverse face 27 in line with a transverse edge of the clip and an inclined face 28 connecting the faces 26 and 27, the corners being rounded at the junctions of the face 28 with the faces 26 and 27.

The ends of the spring plates are speared, as aforesaid, providing at the end of each plate, a pair of inclined edges 29. The main and second plates of the spring are the same length and their edges 29 coincide. When the clip is assembled with the spring, a lug 25 is disposed on either side of the speared ends adjacent thereto of the main and second plates, with the faces 28 adjacent respectively the edges 29 of the main and second plates.

The purpose of the lugs 25 is as follows: Although the present clip is designed so that it will not injure the spring end due to the load transmitted from the clip to the spring, there will be times when a main plate will break across its orifice 4. If there were no lugs 25 present, the broken portion would be free to move outward until it dropped from the spring. This would result in the clip tilting and only being partially supported on the main plate, which is a condition which would have serious consequences. However, the lugs 25 prevent movement of the broken portion longitudinally outward away from the spring and hold it in its normal position so that the clip remains on an even seating and no harm results from the breaking of the main plate. This feature of the present invention allows the use of a spring having a broken main plate end until it is convenient to replace the main plate, 20 without danger of further injury to the spring or clip.

The broken portion is, of course, held against lateral displacement by the lugs and from dropping vertically downward by the second plate 5 adjacent it. If the second plate end should break it will also be held in place by the lugs 25 and the third plate 7 adjacent thereto. However, breakage ordinarily only occurs in the main plate.

The speared spring ends and lugs 25 afford a 30 convenient combination for accomplishing the aforesaid feature of the invention. However, various other means may be employed to accomplish the same results. For instance, if the plate ends were square, a flange projecting from the 35 edge of the clip so that it overlapped the edge of the main plate, would prevent outward longitudinal movement of a broken end portion. This flange could also be employed in the case of a speared main plate if desired.

40 While there has been hereinbefore described an approved embodiment of this invention, it

will be understood that many and various changes and modifications in form, arrangement of parts and details of construction thereof may be made without departing from the spirit of the invention and that all such changes and modifications as fall within the scope of the appended claims are contemplated as a part of this invention. 5

The invention claimed and desired to be secured by Letters Patent is:

1. A plate spring having a plurality of consecutive plates including an outer plate, provided each at a corresponding end portion with an opening, said openings being combined to form a receptacle having a mouth open to the exterior at the outer face of said outer plate, said outer plate being cut away at its corners providing clip-abutting edges; a clip having a body provided with an outer face and an inner face, a lug projecting from said inner face, said body inner face being disposed opposite said outer plate outer face and said lug extending into and having a part projecting beyond said receptacle, said lug being insertible in and removable from said receptacle through said mouth, and a pair of lugs projecting from said inner face at opposite 25 sides of said clip, one adjacent each of said edges, preventing movement of the adjacent portion of said outer plate theretoward; and means coacting with said part to secure said clip to said spring. 20

2. A plate spring having a plurality of consecutive plates including an outer plate, and a spring hanger clip carried by said spring at an end thereof, having an outer face, and an inner face in engagement with said outer plate, and a wear plate disposed on said outer face, said 30 clip having longitudinally spaced flanges engaging opposite ends of said wear plate and holding said wear plate against displacement, said wear plate being removable from said clip for replacement by sliding transverse movement. 35
